CLAIM

The ornamental design for a portable wipes heater, as shown and described.

DESCRIPTION

FIG. 1 is a front, right side, top perspective view of a portable wipes heater showing my new design;

FIG. 2 is a rear, right side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side, top perspective view of the portable wipes heater when it is in charging; and,

FIG. 10 is a perspective view of the portable wipes heater when it is in an open condition such that the heated wipes can be accessed.

The broken lines depict portions of the portable wipes heater that form no part of the claimed design. The additional broken lines shown in FIG. 9 represents the portion of a charger and forms no part of the claimed design. The additional broken lines shown in FIG. 10 represents the heated wipes and forms no part of the claimed design.

1 Claim, 10 Drawing Sheets
